Atty's.*

UNITED STATES PATENT OFFICE

JOHN C. BROOKS, OF PATERSON, NEW JERSEY, ASSIGNOR TO DRAPER CORPORATION,
OF HOPEDALE, MASSACHUSETTS, A CORPORATION OF MAINE

LOOM

Application filed July 13, 1927. Serial No. 205,506.

The object of my invention is to make the loom more simple in construction and more certain in its operation, and, to provide a filling stop motion active between the filling supply and the pick measuring mechanism.

The novel features of the invention are fully disclosed in the following specification and accompanying drawings, and are further pointed out in the claims.

10 Referring to the drawings Fig. 1 is a view in elevation at one side of the loom but showing only portions of the loom;

Fig. 2 is a section on the line 2—2, Fig. 1;

Fig. 3 is a detail of the means for disengaging the filling from the pulling-off finger.

In the drawings the ordinary parts of the loom shown are the lay A, breast beam B, framing C, and end of crank shaft D.

Upon the end of shaft D is a sprocket 20 wheel, 1, and upon a stud, 2, in upper end of frame, C, is a sprocket wheel, 3. Carried and operated by these sprockets is a chain, 4, provided with special links, 5 and 6.

Links 5 and 6 have wings 7 and 8. Link 6 25 has a bridge, 9, secured to wings 8, and fast in the center of said bridge 9 is a pin, 10, on which is secured a roller, 11.

Adjustably bolted to framing C is a filling guide, 13, provided with holes, 14, 15.

30 Mounted on the lay A is an air-discharging nozzle 32 retained thereon by a clip 33, this nozzle being such as is usually employed in looms of this type for blowing the filling through the shed.

35 The filling 40, carried on cone, 41, supported by bracket, 42, secured on framing C, passes up through hole, 43, in end of beam B, through holes 14 and 15 in filling guide 13 and through air nozzle 32.

40 As the sprocket chain moves, roller 11 engages filling thread and draws off a desired length; determined by the distance between guide 13 and sprocket wheel 3.

As link 5 begins to bend, in conformation 45 to sprocket 3, loop 12 is moved outwards, dot-

ted lines Fig. 1, pushing filling of thread off roller 11 thus forming a loose loop at filling to be blown within the warp-sheds.

Having described my invention, what I claim as new and desire to secure by Letters 50 Patent is—

1. In a loom having a source of filling supply and means to insert lengths of filling in the shed, the combination with a sprocket chain, of upper and lower sprocket wheels 55 over which it passes, means on the sprocket chain to engage said filling thread between the filling-inserting means and the source of supply and draw off a length of filling thread, and means on the chain and rendered opera-

60 tive as the chain passes over the upper sprocket wheel to disengage said filling thread from the pulling-off means.

2. In a loom having a source of filling supply and means for inserting filling in the 65 shed, the combination with a lay, of a crank shaft for operating the latter, a sprocket chain actuated by the crank shaft, upper and lower sprocket wheels over which the sprocket chain passes, means on the sprocket chain to engage the filling thread between the source of supply and filling-inserting means

70 and thereby draw off a length of filling thread from the source of supply, and means on the sprocket chain and rendered operative as the 75 chain passes over one of the sprocket wheels to disengage the filling thread from the pulling-off means.

3. In a loom having a source of filling supply and means for inserting the filling in the 80 shed, the combination with a lay, of a crank shaft by which the lay is operated, a sprocket wheel on said crank shaft, a sprocket chain passing over said sprocket wheel and provided with links, and another sprocket wheel over 85 which said chain passes, a finger on said chain adapted to engage the filling thread and draw off a length thereof from the source of supply, and means rigid with one of the links to disengage the filling thread from the finger 90

as the link passes over one of the sprocket wheels.

4. In a loom having a source of supply and means to insert filling in the shed, the combination with a lay, of a sprocket chain having links, means on the sprocket chain to engage said filling thread between the filling-inserting means and the source of supply and throw off a length of filling thread, and means rigid with one of the links and actuated by the movement of the chain passing over the sprocket wheel to disengage the filling from said finger.

JOHN C. BROOKS.
